UNITED STATES PATENT OFFICE.

WILLIAM W. BAYS, OF CHARLOTTE, NORTH CAROLINA.

DISH-WASHING MACHINE.

1,097,702.

Specification of Letters Patent. Patented May 26, 1914.

Application filed October 28, 1912. Serial No. 728,310.

To all whom it may concern:

Be it known that I, WILLIAM W. BAYS, citizen of the United States, residing at Charlotte, in the county of Mecklenburg and State of North Carolina, have invented certain new and useful Improvements in Dish-Washing Machines, of which the following is a specification.

This invention relates to devices for washing dishes, and has for one of its objects to provide a simply constructed and conveniently arranged device whereby soiled dishes are washed or cleansed and whereby the dishes are forced downwardly through the cleansing liquid and the cleansing liquid forced upwardly and distributed over the dishes.

Another object of the invention is to provide a device whereby the dishes are thoroughly washed or cleansed without subjecting them to harsh treatment or agitation so that the most fragile and delicate dishes can be washed in the improved device without danger of breakage.

Another object of the invention is to provide a device of this character wherein the dishes are subjected to the action of co-acting air currents and jets of the cleansing or rinsing liquid, and wherein the cleansing or rinsing liquid is applied to all sides of the dishes and from all directions.

Another object of the invention is to provide a device of this character wherein provision is made for so supporting the dishes that those of a fragile and delicate material are supported and held from lateral movement, and thus prevented from being fractured or otherwise injured.

Another object of the invention is to provide a device of this character wherein the parts are readily separable for cleansing and the restoration of broken and impaired parts.

Another object of the invention is to provide a simply constructed device which is safe and simple and easily operated and without weariness to the operator.

Another object of the invention is to provide a device whereby dishes of varying sizes and forms may be simultaneously washed and without the necessity for the hands of the operator coming in contact with the cleansing liquid.

Another object of the invention is to pro-

vide a simply constructed device whereby the dishes after being washed may be drained and rinsed without handling the individual dishes.

With these and other objects in view, the invention consists in certain novel features of construction as hereinafter shown and described and then specifically pointed out in the claim, and in the drawings illustrative of the preferred embodiment of the invention.

Figure 1 is a side elevation of the improved device. Fig. 2 is a plan view of the improved device in its simpler form with the upper portion in section on the line 2—2 of Fig. 1. Fig. 3 is a vertical sectional elevation on the line 3—3 of Fig. 1. Fig. 4 is a plan view in section on the line 4—4 of Fig. 3. Fig. 5 is an enlarged perspective view of one of the dish separating bars. Fig. 6 is an enlarged perspective view of the cup and glass holder. Fig. 7 is a sectional detail on the line 7—7 of Fig. 6. Fig. 8 is a plan view of the supporting cage, with the suspending and operating bars in section on the line 8—8 of Fig. 3. Fig. 9 is a plan view of the dish holder with the dish supporting rack removed. Fig. 10 is a side view of a modified form of the air chamber, and a modified form of the sleeve fitting over the air and water conduit.

Corresponding and like parts are referred to in the following description and indicated in all the views of the drawings by the same reference characters.

The improved device comprises a receptacle 10 for the cleansing liquid which may be of any suitable shape and constructed of any suitable material, but is preferably cylindrical in form and open at the upper end and provided with a draw-off device 11 whereby the cleansing liquid may be removed. The receptacle 10 is also provided with lifting handles 12 of suitable construction. Connected to the receptacle 10 at one side is a socket 13 to support a standard 15 to which an operating lever 16 is pivotally connected at 17, the object to be hereafter explained.

The lever 16 is provided with a holding spring 19 which retains its inner end normally in upward position. A stop member 20 is also connected to the standard 15 and

extends into the path of the lever 16 so that when the latter is moved downwardly to a certain degree, the stop will engage the lever and hold the latter in its downward position, the object to be hereafter explained.

Formed upon opposite sides of the receptacle 10 are vertical guides 18 which preferably extend the full length of the receptacle.

Slidably disposed within the receptacle 10 is a cage or frame for supporting the dish holding portion of the device and comprises a lower annular member 21 and an upper annular member 22, the annular members being connected in spaced relations by a plurality of bands or straps 23. The lower member 21 is likewise provided with a plurality of transverse supporting strips 23 upon which the dish supporting receptacle rests, as hereafter explained.

Any required number of the straps 23 may be employed, but preferably two will be used, as shown, and located at opposite sides of the annular members.

Connected to the annular members at opposite sides and spaced at equal distances from the straps 23 is a lifting member comprising spaced vertical sides 24 and a transverse connecting member 25. The members 24-25 are preferably constructed from a single strip of metal bent into elongated U-form and riveted or otherwise secured to the members 21-22. At their lower ends 26 the members 23 are directed inwardly, as shown at 26, while the lower ends of the members 24 are likewise directed inwardly, as shown at 27. Connected to the under faces of the inturned terminals 26-27 are concussion springs 28 which rest upon the bottom of the member 10 when the supporting cage is in its lower position, and are designed to receive the jar and concussion when the supporting member is moved downwardly and thus prevent injury to the dishes contained in the holder, as hereafter more fully explained. Connected to the upper member 25 of the cage support is a guide device including a transverse upper member 29 and vertical side members 30, the latter being movably disposed in the guides 18 of the outer receptacle 10, while the upper member 25 of the cage support is connected to the transverse member 29.

Depending from the lever 16 at its inner end is a rod 31 having a hook 32 at its lower end for engaging through an aperture in the member 29. By this simple means it will be obvious that when the parts thus described are assembled the depression of the outer end of the lever 16 will elevate the inner end and correspondingly elevate the cage device.

The receptacle in which the dishes are directly disposed comprises a casing 33 con-

forming in outline to the annular members 21-22 and fitting within the same and resting by its lower edge upon the transverse bars 23 and likewise upon the upper faces of the inturned terminals 26-27. The member 33 is provided with numerous relatively large perforations 14 to permit the cleansing liquid to freely pass, and is provided with a lifting bail 34 at its upper edge, the bail conforming in outline to the upper edge 75 of one-half of the upper edge of the member 33 so that when the bail is not in use it lies in close engagement with said upper edge.

At its lower end the member 33 is connected by a plurality of transverse bars 35 to form a support for a downwardly opening air chamber 36, the latter having an outwardly downwardly directed lateral flange 37 at its lower edge and with a tubular upwardly directed projection 38 at its apex or upper end. The flange 37 is provided with numerous relatively large perforations 39, and slidably disposed over the tubular projection 38 is a sleeve 40. Connected to the lower end of the sleeve is a conical member 41 formed of relatively coarse wire netting, and connected to the member 41 at its lower end is an annular downwardly and outwardly inclined ring 42 having numerous 95 apertures 43.

The ring 42 rests upon the bars 35 of the member 33 and is supported thereby. Intermediate supporting lugs 61 project inwardly from the lower edge of the member 100 33 and assist in supporting the flange 42.

The member 41 together with its sleeve 40 and ring 42 are removable from the member 33. The conical member 41 is relatively flat, while the conical member 36 is relatively acute so that a considerable space is left between the members 41 and 36.

Fitting over the upper portion of the projection 38 is a sleeve 44 from which rods 45 rise at the upper end. Connected to the rods 45 and spaced above the upper end of the member 38 is a relatively large plate 46, and attached to the lower face of the plate 46 is an inverted cone 47, the point of the cone coming about flush with the upper edge 115 of the member 38. By this means an effec-tual deflector device is produced which distributes the rising liquid over the dishes resting upon the conical member 41, as hereafter explained.

The member 10 is provided at its upper end with a closure 48 having a depending rim 49 which bears within the upper edge of the member 10 and with recesses 50 in the opposite sides through which the members 125 24 and 30 operate. The member 48 is provided at one side with a portion 51 hingedly united at 52 to the body of the cover 48 and provided with a depending rim 53 corresponding to and forming a continuation of 130

the rim 49. By this means a portion of the cover may be elevated to enable the dishes contained in the member 33 to be inspected when required.

5 Rising from the cover 48 is a reduced rim 54 which incloses a portion of the upper side of the member 48, and the member 48 is provided with numerous apertures 55 within the space inclosed by the rim 54. By this 10 arrangement means are provided for supplying the receptacle 10 with the cleansing liquid, or with the rinsing liquid as may be preferred, without the necessity for removing the cover or the other parts.

15 In Fig. 6 a device is illustrated which may be employed for supporting tumblers, cups, and similar dishes or vessels of frail texture within the holder 33, and is designed preferably to be used independently 20 of the support 41, but may be used in connection with the member 41.

When the device shown in Fig. 6 is employed the member 41 may or may not be removed as the operator may elect.

25 The tumbler or cup supporting attachment comprises a band 56 adapted to be inserted within the member 33 and provided with numerous split rings 57 extending inwardly from its upper edge and with an annular supporting member 58 and radial bars 59, the latter being arranged in pairs with one pair of the bars located in vertical alignment with one of the split rings 57. The rings 57 are designed to support cups, 30 glasses and like dishes which rest by their lower ends upon the radial members 59. The rings 57 are preferably provided with inwardly directed extensions 60 which provide means for manually distending the 35 rings to adapt them to glasses or cups of different sizes. The extensions 60 are also designed to receive the handles of tea cups and like articles and thus prevent them from fracture during the washing and rinsing 40 action.

In the operation of cleansing dishes with the improved device the outer end of the lever 16 is depressed until it engages the hook of the locking bar 20 which action correspondsingly raises the cage upwardly in the 45 dish holder in convenient location to receive the dishes, or the dish holder may be removed from the cage and placed upon a table or other support, and the holder with the dishes therein then placed back within the cage. The dishes are uniformly deposited within the holder and upon the support 41 in reclining position and with substantially the same general inclination as the 50 support 41. The dishes are preferably placed with their inner or concave sides downwardly, or toward the support 41, as illustrated in Fig. 3. The cover 48 together with its hinged portion 51 may then 55 be located upon the member 10 with the re-

cesses 50 opposite the members 24-30 and with the hinged portion 51 at the opposite side of the member 10 from the standard 15. The cleansing liquid is then poured into the rim 54 and passes through the apertures 55 70 and over the dishes below. This action constitutes the preliminary washing or cleansing of the dishes, but if preferred the cover 48 may be left off and the cleansing liquid poured directly upon the dishes. The lever 16 is then released from the locking member 20 and operated rapidly to cause the dish supporting device to vibrate vertically through the cleansing liquid and produce the required cleansing action. As the dish 75 receptacle is moved downwardly the air is caused to move upwardly in the conical member 36 and into the extension 38 and is thrown violently by the deflector 47-46 outwardly and downwardly and in contact 80 with the upper surfaces of the dishes. Thus as the receptacles move downwardly the lower sides of the dishes engage against the cleansing liquid while a relatively 85 large portion of the latter is moved upwardly through the member 38 and thrown violently upon the outer sides of the dishes. As the dish receptacle is moved upwardly at the return stroke of the lever the reverse action takes place as will 90 be obvious. By this means the dishes are moved rapidly upwardly and downwardly through the cleansing liquid and the latter forcibly thrown in contact therewith, both at the lower sides and the upper sides. The 95 cleansing action is thus very thorough and complete and every part of each dish is subjected to the action of the cleansing liquid a number of times, or practically at each 100 stroke of the lever.

105 The improved device is simple in construction, can be inexpensively manufactured and of any required size or capacity, and is equally adaptable for a small family or for the largest hotels or restaurants.

110 In Fig. 3 the member 36 is shown with inclined sides, while in Fig. 10 this member is shown in bell or inverted bowl shape, or with curved sides.

In Fig. 10 also a modified form of the 115 sleeve 44 is shown formed of wire cloth, as shown at 62, and extending above the sleeve 38 and carries the deflector plate 46 and its cone 47. The netting thus replaces the rods 45. The air and water rising through the 120 sleeve 38 freely passes through the meshes of the netting.

In Fig. 5 is shown a device which will be employed to hold the dishes separated one from the other when required to permit the 125 cleansing liquid to flow more freely between them. These devices are formed of metal strips bent into a plurality of return bends, and may be of any required size and any required number may be employed. These 130

4
separating strips will not be required except where the dishes are of such uniform shape that they will closely "nest" when deposited in the holder.

5 Either form may be employed and it is not desired to limit the invention to any specific form of this portion of the apparatus.

When it is desired to wash or cleanse the dish holder the sleeves 44 and 40 are removed together with the deflector and the foraminous supporting member and the cage likewise removed. By this means the parts are in separated position and can be readily 16 and separately cleansed. By arranging the parts to be thus separated, broken or impaired portions may be readily removed without discarding the remainder of the apparatus.

Having thus described the invention what 20 I claim is:

A device of the class described comprising a receptacle for a cleansing liquid, a supporting cage within the receptacle, a dish holder supported loosely within the cage, a 25 downwardly opening air chamber supported rigidly within the holder and having an upwardly directed air and water conduit, and means for vertically moving the cage and the dish holder and the air chamber carried 30 thereby within the receptacle.

In testimony whereof I affix my signature in presence of two witnesses.

WILLIAM W. BAYS. [L. S.]
